UNITED STATES PATENT OFFICE.

GEORGE D. CARON, OF DANIELSON, CONNECTICUT, ASSIGNOR TO JOSEPH BODO, OF DANIELSON, CONNECTICUT.

SHADE-ROLLER BRACKET.

1,105,486.

Specification of Letters Patent.

Patented July 28, 1914

Application filed October 22, 1912. Serial No. 727,221.

To all whom it may concern:

Be it known that I, GEORGE D. CARON, a citizen of the United States, residing at Danielson, in the county of Windham and State of Connecticut, have invented new and useful Improvements in Shade-Roller Brackets, of which the following is a specification.

This invention relates to shade roller brackets, and has for an object to provide a bracket of this character which can be pressed from a single piece of suitable sheet metal and which will be of a design wherein means are provided for holding the shade roller against accidental displacement from the bracket.

In the drawing, forming a portion of this specification and in which like numerals of reference indicate similar parts in the several views: Figure 1 is a perspective view of the companion shade brackets showing a roller operatively associated therewith, the roller being in dotted lines. Fig. 2 is a side elevation of one of the brackets, the washer being shown in section.

The brackets 1 and 2, shown in Fig. 1 of the drawing, are each stamped or pressed from a single piece of suitable sheet metal and each is formed to provide a supporting shank 3 which is formed at its outer end to provide a head 4 and at its inner end to provide a shoulder 5 from which extends an attaching shank 6 which is threaded through the major portion of its length and preferably pointed at its outer end, as shown, the material from which the bracket is stamped being of the same thickness throughout. At the inner end the shank 6 has mounted thereon a guard washer 7 which is adapted to bear against the window frame on which the bracket is adjusted, the shoulder 5 of the bracket being designed to bear against the washer so that the inward adjustment of the brackets in the frame is limited. From this construction it will be seen that both brackets can be accurately set upon the frame so as to hold the shade roller in parallel relation with respect to the window.

The head 4 at the outer end of the shank 3 of the bracket 1 is disposed substantially wholly below the plane of the said shank, and as illustrated, the head is formed with a retaining slot 8 for the rectangular spring tension trunnion of the shade roller. The inner wall of the slot is inclined down-

wardly, as at 9, and the upper end of the wall is disposed immediately opposite the downwardly and inwardly inclined surface 10 at the inner end of the shank 3. The outer wall 11 of the slot extends downwardly and forwardly toward the wall 9 of the slot and it is connected therewith by the downwardly and outwardly inclined bottom wall 12 of the slot. The slot is formed to provide a guard shoulder 13 which is located immediately beneath the inner end of the shank 3, as shown. The construction of the slot described is such that all of its walls are arranged in intersecting planes with respect to each other so that the lowest point of the slot is directly beneath the guard shoulder 13. In view thereof, it will be observed that when the spring tension rectangular trunnion of the shade roller is positioned in the slot 8 it will be disposed therein directly beneath the said guard shoulder 13 and in juxtaposition with the outer wall 11 of the slot, the said wall 11 operating to direct the trunnion toward the guard shoulder so that the same will be engaged by the shoulder on accidental upward movement of the trunnion in the slot. With a view of facilitating the engagement of the trunnion in the slot the inclined surface 10 at the inner end of the shank 3 extends upwardly beyond the upper end of the wall 9, acting as a guide so as to cause the trunnion of the roller to be readily extended into the receiving slot of the bracket. The shank 3 of the bracket 2 has its head 4 disposed substantially below the plane of the shank and it is formed centrally with an opening 14 for receiving the cylindrical fixed trunnion of the shade roller. The washer 7 on the threaded shank 6 of each bracket is loose so that when the shoulder of the bracket is brought to bear against the washer the latter will not rotate against the surface of the window frame. From this construction it will be seen that I guard against marring the window frame on attaching the bracket thereto.

I claim:

A shade roller bracket comprising a member provided with an integral attaching portion and a head carried by the attaching portion and having a trunnion receiving slot therein, including outer walls lying to one side of the vertical center of the head and arranged in substantially superimposed relation, a shoulder connecting said outer

walls with each other and extending at right angles to the plane of said walls, an inner wall terminating at its outer end slightly below the uppermost outer wall and inclined 5 downwardly and outwardly in the direction of the vertical center of the head and toward the lower end of the lowermost outer wall so that the slot is of an increased width intermediate its upper and lower ends and 10 then restricted from its intermediate portion and gradually flared to the upper end

of the head and a connecting bottom wall lying parallel with the shoulder and serving when engaged against the trunnion to hold the latter operatively disposed beneath said shoulder. 15

In testimony whereof I affix my signature in presence of two witnesses.

GEORGTH D. CARON.
